UNITED STATES PATENT OFFICE.

MARTIN SORENSEN, OF SEATTLE, WASHINGTON.

DETACHABLE BUTTON.

1,368,065.

Specification of Letters Patent. Patented Feb. 8, 1921.

Application filed March 1, 1920. Serial No. 362,612.

To all whom it may concern:

Be it known that I, MARTIN SORENSEN, a citizen of the United States, and resident of the city of Seattle, county of King, and State of Washington, have invented certain new and useful Improvements in Detachable Buttons, of which the following is a specification.

This invention relates to improvements in buttons, and more particularly to buttons of a detachable character wherein two parts are adapted to be locked together from opposite sides of a garment, to secure the button in position for use.

It is the principal object of the invention to provide a button having a head portion provided with openings for receiving the locking heads of a pair of prongs extended from a locking shoe, or disk, after the said prongs have been projected through a garment or the like, in such manner as to secure the head in functional position.

It is also an object of the invention to provide a button of this character wherein the head is equipped with an opening which will permit the insertion of a tool to release the locking member and the disconnection of the parts.

In accomplishing these and other objects of the invention, I have provided the improved details of structure, the preferred forms of which are illustrated in the accompanying drawings, wherein—

Figure 1 is an enlarged perspective view of the two parts of a button embodying the present invention, shown in detached relation.

Fig. 2 is a transverse, sectional view of the same when attached.

Fig. 3 is an inner face view of the button head; particularly illustrating the opening and arcuate slot wherein the locking prongs and heads are inserted.

Referring more in detail to the drawings: 1 designates the head of a button embodying the present invention, comprising an outer circular wall 2 provided with a central opening 3, and an inner wall 4 of smaller diameter than the outer wall and spaced there-

from by a connecting wall or neck 5, which, with the outer wall 1, forms a peripheral flange 6 for entering the button hole of the article with which the button is used.

Adapted to be detachably secured to the head, is a locking disk, or shoe 7, of about the same diameter as the wall 4, or larger if

desired, and provided with two spaced apart prongs, or pins, 9, that extend perpendicularly therefrom and which, at their outer ends, are equipped with pointed heads 10, 60 having inwardly facing shoulders 11 at their outer sides facing toward the disk.

To lock the parts together, the two prongs are projected, through openings 12 and 13 in the inner wall of the head 1; the opening 12 65 being only of sufficient size to receive the head of the prong extended therein, while the opening 13 has an arcuate slot 14 leading therefrom, with the opening 12 as a center, into which the other prong may move, 70 and in doing so will shift the heads 10 into locking relation with the button head 1.

A spring wire 16 is secured at one end within the button head with its free end extended across the slot 14. The wire is yieldable in one direction to permit it to be pressed from the path of the head when the parts are being locked together but will not yield in the other direction and thus will retain the parts in locked position. 80

In using the button, the locking disk is placed on the inside of the garment and the prongs 9 pressed outwardly therethrough to expose the heads 10 at the outer side. The button head is then applied to the prongs 85 by inserting one prong into the opening 12 and the other into the enlarged end 13 of the slot 14 and then turning the head so that the latter prong will move along the slot 14 toward its closed end and will pass back of 90 the spring wire 16. When the prongs are in this locked position the shoulders 11 will each engage the under sides of the wall 4 and will prevent the parts from being detached. 95

If it is desired to detach the parts, a pointed tool may be inserted through the opening 3 in the outer wall of the head 1 and the spring wire 16 pressed aside to permit the prong to move along the slot to the 100 opening 13 which will permit unseating of the shoulders and the disconnection of the parts.

What I claim as new is:

1. A button of the character described 105 comprising, a head portion having two spaced openings therein and having an arcuate slot leading from one of said openings about the other as a center, a locking shoe having a pair of prongs extending from one 110 side thereof adapted to project into said head openings and having locking heads at

their ends which lock within the head when the shoe is turned to move one of said prongs into the arcuate slot and yieldable means secured within the head for retaining the 5 prongs in locked relation to the head.

2. A button of the character described comprising a head portion having two spaced openings therein and having an arcuate slot leading from one of said openings 10 about the other as a center, a locking shoe having a pair of prongs extending therefrom adapted to be projected into said head openings and having shouldered heads at their ends for locking the parts together 15 when the shoe is turned to move one of said prongs into the arcuate slot, and a spring secured to the button head with a yieldable end extending across the said slot in a manner to permit the prong to pass but to prevent 20 its return to the opening at the end thereof.

3. A button of the character described

comprising a head portion having inner and outer spaced apart walls, the outer wall having a central opening therein and the 25 inner wall having two spaced openings therein with an arcuate slot leading from one opening about the other as a center, a locking shoe having a pair of prongs extending therefrom to be projected into said 30 inner wall openings and having shouldered heads at their ends for locking the parts together when the shoe is turned on the head to move one of said prongs into the arcuate slot, and a spring wire secured within the 35 head having a free end extending yieldably across the slot to normally prevent removal of the prong from the slot but which may be pressed aside by the insertion of a pointed tool through the opening of the outer wall to 40 permit disconnection of the parts.

Signed at Seattle, Washington, this 12th day of February, 1920.

MARTIN SORENSEN.
